UNITED STATES PATENT OFFICE.

CARL H. SUNDBERG, OF CHICAGO, ILLINOIS.

VEGETABLE-MASHER.

1,373,843.

Specification of Letters Patent.

Patented Apr. 5, 1921.

Application filed September 7, 1920. Serial No. 408,493.

To all whom it may concern:

Be it known that I, CARL H. SUNDBERG, a citizen of the United States, residing at Chicago, in the county of Cook and State 5 of Illinois, have invented new and useful Improvements in Vegetable-Mashers, of which the following is a specification.

My invention relates to certain details of construction in vegetable mashers whereby 10 the mashing process is improved and the operation hastened, furthermore the device is so constructed that it can be easily and quickly made at a comparatively low cost and yet is durable and efficient.

15 These several advantages and objects are attained by so making the mashing bars that they will crush and not cut the material as they are forced through the same and extending angles and corners are eliminated.

20 To describe my invention so that others versed in the art to which it pertains can make and use the same I have illustrated it on the accompanying sheet of drawing 25 forming a part of this specification, and in which:—

Figure 1, is a perspective view of a vegetable masher embodying my invention and Figs. 2 and 3 are vertical cross sectional 30 views taken on planes at right angles to each other.

Similar reference characters refer to similar parts throughout the several views.

The frame of the masher is of the usual 35 form comprising two wires 4, 4, similarly formed with a straight base 5 being the middle of the wire, and with the ends of the wire extending upward a short distance and then together at a common center where 40 the four ends of the two wires are twisted together and secured in a handle 6.

The construction thus far described forms no part of my invention. The mashing bars 7, of which any desired number may be employed, are made preferably of half round wire with the flat surface facing down and the rounded portion up. The bars 7 are

spaced apart suitably for the kind of vegetable to be mashed and have their ends rigidly secured to the straight base portions 5 50 of the wires 4 preferably by spot welding the same together. The ends of the bars 7 have their lower corners rounded as clearly shown at 8 in Figs. 1 and 3.

The purpose of forming the bars 7 as 55 shown, i.e., flat on the lower side and round on the upper side is to crush or mash the material as the device is pushed down through the same and when it is withdrawn upwardly the material will not cling to the 60 bars 7, but will naturally slide off of the rounded portion. The rounded corners 8 protect the hands of the person using the device especially when cleaning or washing the same.

It will be understood that the form, size and arrangement of the parts may be varied without in the least departing from the scope of my invention.

Having thus fully described my invention what I claim as new and desire to secure by Letters Patent of the United States is:—

1. In a device of the class described, mashing elements provided with flat lower 75 surfaces and rounded upper surfaces.

2. In a device of the class described, a suitable frame, a plurality of mashing bars rigidly secured to the frame provided with flat lower surfaces and rounded upper surfaces.

3. In a device of the class described, a suitable frame, a plurality of parallel mashing bars arranged in the same horizontal plane rigidly secured to the frame provided with flat lower surfaces and rounded upper surfaces.

In testimony whereof I have signed my name to this specification in presence of a subscribing witness this 4th day of September, 1920, at Chicago, Illinois.

CARL H. SUNDBERG.
